UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,072,737.

Specification of Letters Patent.

Patented Sept. 9, 1913.

Application filed November 14, 1912. Serial No. 731,236.

To all whom it may concern:

Be it known that I, DAVID S. KENNEDY, a citizen of the United States, and a resident of Brooklyn, county of Kings, and State 5 of New York, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine or 10 magazines in the order in which their characters are to appear in print and then assembled in line, the composed line transferred to the face of a mold, the mold filled with molten metal to form a slug or linotype 15 against the matrices which produce the type characters thereon, and the matrices thereafter returned through a distributing mechanism to the magazine or magazines from which they started.

More particularly, it relates to machines of the kind referred to, wherein a plurality of magazines is employed and arranged so that any selected one thereof may be brought into operative relation to the assembling and distributing devices. In the accompanying 20 drawings, I have shown my improvement in connection with the style particularly illustrated in the application for Letters Patent of John R. Rogers, Serial No. 624,426, wherein the magazines are movable relatively to the assembling mechanism, etc., although it could be similarly applied to machines wherein the magazines are stationary and the other coöperating means 25 are moved relatively thereto.

One of the principal features involved is the division of the escapement into two separable parts, one of which is connected to the magazine, and the other to the throat or other assembling device, which receives the matrices therefrom, these parts being 30 so arranged that they are located in operative relation to each other only when the corresponding magazine is brought into action. More specifically, the actuating member of the escapement is shown as mounted on the receiving throat in position to engage any one of several coöperating members connected to the different 35 magazines.

In Letters Patent of the United States to P. T. Dodge, No. 883,180, a somewhat similar arrangement is disclosed, but the present construction differs therefrom in numerous material respects. For instance, in the 40 said Dodge patent, not only is the receiving throat movable vertically in relation to the magazines, but in addition the magazines themselves are capable of a horizontal movement to allow the engagement and disengagement of the parts. In my improved 45 construction no such additional movement is necessary, as the magazines are moved as a whole and in a straight path in relation to the throat. Moreover, in said Dodge 50 patent, the entire escapement is connected to the throat in such manner that the release of the matrices is completely controlled thereby outside of the magazine; and the 55 magazines are each provided with a rocking bar having lips passing into the magazine to engage the contained matrices, which bar is operated to unlock the matrices when the outside escapement is actuated. In the present 60 form, as before stated, I divide the 65 escapement into two distinct parts, one attached to the throat, and the other to the magazine, so that when connected they constitute together a single escapement to control the release of the matrices.

In the accompanying drawings, I have shown my invention in preferred form and by way of example, and as applied to the specific kind of machine already mentioned, but obviously many variations and modifications 70 therein, and in its mode of application, may be made without departure from its spirit. Thus, for instance, it may be applied to other forms of typographical machines, such as type setters, type casters, and 75 the like, or machines which handle type or dies instead of matrices. Generally speaking, I desire it to be understood that I do not limit myself to any specific form or embodiment, except in so far as such limitations are specified in the claims.

Referring to the drawings: Figure 1 is a side view, partly broken away and in section, of a portion of a linotype machine with my improvements embodied therein; and 80 Fig. 2 is a transverse vertical section on an enlarged scale.

As in the said Rogers application, a plurality of movable magazines A is employed in connection with shifting means B, where- 85

by any selected one thereof may be brought into operative relation to the distributing devices, comprising the screws O, rail P, and entrance Q, and to the receiving throat C, through which the released matrices pass to the front-plate D and to the other assembling devices, all in the manner well understood in the art.

Each of the magazines A is provided with a series of escapement devices, each comprising a lever L and a single pawl l, which is normally projected into the magazine channel by the spring L¹. The movement of the lever L in the opposite direction against the spring withdraws the pawl from the channel and permits the forward travel of the matrices X therein, the lever being thus shifted in the manner subsequently to be described. The pawls l are normally in their locking position and the matrices are therefore held thereby during the shifting of the magazines. It will be seen that the parts L, l, and L¹, not only serve as locking devices in the manner described, but also constitute a portion of the complete escapement, the other portion of which is mounted on another part of the machine.

The throat C is provided with a pivoted lever M, carrying the pawl m, which is normally held in its retracted or inoperative position by the spring M¹. The operation of the lever M is controlled by the connected reed N, which in turn is actuated through any suitable form of keyboard connections N¹, in the customary manner. The inner arm M² of the lever M is located in proximity to the outer end L² of the escapement lever L of the magazine in operation, in such manner that when the reed N swings the lever M about its pivot, its arm will engage the lever L and move it against the force of the spring L¹. When the parts are at rest, the levers L and M are held out of the path of each other by their respective springs, so as to permit the free and unimpeded shifting of the magazines. It will also be noted that a single series of escapement levers M is thus adapted to coöperate with any one of the several series of escapement levers L corresponding to the particular magazine in operative position.

The operation of the parts is as follows, assuming the upper magazine A to be in action, as shown in Fig. 2, with the pawl l engaging the upper ear of the lowermost matrix X: The reed N moves downwardly and swings the lever M about its pivot against the force of the spring M¹, as shown in dotted lines, and projects the pawl m into the throat C. Simultaneously its arm M² engages the end L² of the lever L, and thus moves the latter about its pivot against the force of the spring L¹, withdrawing the pawl l from the magazine channel. The matrices X now pass downwardly until the

lowermost one is arrested by the pawl m. The reed N next moves upwardly and permits the spring M¹ to turn the lever M in the opposite direction and thus to withdraw the pawl m from the throat C, and the lowermost matrix drops into the front-plate D. The simultaneous release of the lever L allows the spring L¹ to act and project the pawl l into the magazine channel in time to engage beneath the upper ear of the next matrix, and the parts are again in their normal position.

It will be noted that the distance between the pawls l and m is considerably greater than that between the pawls of an ordinary escapement, and it is preferably so determined that when the lowermost matrix is arrested by the pawl m, it projects slightly beyond the throat C into the matrix channel, and to a sufficient extent to hold the next matrix therein with its upper ear slightly above the pawl l, in such manner that when the pawl m is withdrawn from the throat and the pawl l projected into the channel, the latter will have sufficient time to move into position beneath the ear. This arrangement as to distance and proportion is preferred, although not absolutely essential to the practice of my invention, as if necessary the pawls could be separated to a still greater extent and the magazine pawl be thus permitted to rise in closer relation to the matrix ear. This and other variations in the construction and application of my improved devices will suggest themselves to those skilled in the art and still be comprised within the scope of the invention.

Having described my invention, its construction and mode of operation, what I claim and desire to secure by Letters Patent of the United States is:

1. In a typographical machine having a magazine for the type or matrices, an escapement comprising two separate portions each provided with a single engaging member for the type or matrices, one portion being connected to the magazine and the other portion being mounted exterior thereto.

2. In a typographical machine, the combination of a magazine for the type or matrices and assembling devices, the said parts being arranged so as to be relatively movable, with an escapement comprising two separate portions each provided with a single engaging member for the type of matrices, one portion being connected to the magazine and the other to the assembling devices.

3. In a typographical machine having a magazine for the type or matrices, an escapement comprising two separate portions each provided with a single engaging member for the type or matrices, one portion being connected to the magazine and the other portion being mounted exterior thereto, and

one being controlled in its operation by the other.

4. In a typographical machine, the combination of a plurality of magazines for the type or matrices and assembling devices, so arranged that any selected magazine may be brought into operative relation to the other parts, and each of the magazines being provided with a series of escapement elements, each comprising a single engaging member for the type or matrices, with a single series of escapement elements located exterior to the magazines and each comprising a single engaging member for the type or matrices, the said latter series being adapted to be brought into operative relation to the series of escapement elements of the selected magazine.

5. In a typographical machine, the combination of a magazine provided with a series of escapement elements, each comprising a single engaging member for the type or matrices, with a corresponding series of escapement elements located exterior to the magazine and each provided with a single engaging member for the type or matrices, the respective series being so arranged that the actuation of the exterior elements effects the actuation of the corresponding magazine escapement elements.

6. In a typographical machine, the combination of a magazine provided with a single escapement member to engage the type or matrices therein, with an exterior part provided with a single member to engage the type or matrices, the said members being arranged so that together they control the delivery of the type or matrices.

7. In a typographical machine, the combination of the magazine A for the type or matrices provided with the single escapement pawl *l* and the throat C provided with the single escapement pawl *m*, the said pawls being so arranged that conjointly they control the release of the type or matrices.

8. In a typographical machine, the combination of the magazine A for the type or matrices provided with the escapement lever *L*, single pawl *l* and spring *L*¹, with the throat C provided with the escapement lever *M*, single pawl *m* and spring *M*¹, the said

levers being so disposed that the movement of one actuates the other, thus conjointly controlling the release of the type or matrices.

9. In a typographical machine, the combination of the throat C and a plurality of magazines A, any selected one of which may be brought into operative relation to the throat, each of the magazines A being provided with a series of escapement levers *L*, springs *L*¹ and single pawls *l*, and the throat C being provided with a series of escapement levers *M*, springs *M*¹ and single pawls *m*, the series of levers *M* being so disposed as to engage and actuate the series of levers *L* of the selected magazine to control the release of the type or matrices.

10. In a typographical machine, the combination of a magazine for the type or matrices, and an exterior member, one of said parts being movable freely relatively to the other, with a series of sectional escapements to control the release of the type or matrices from the magazine, one set of said sections being provided with single matrix-engaging portions and connected to the magazine and the other set being provided with single matrix-engaging portions and connected to the said member, and the said sets being so arranged as to permit the free and unimpeded relative movement before mentioned.

11. In a typographical machine, the combination of a magazine for the type or matrices, and an escapement therefor comprising two alternately acting single matrix engaging members, one of said members being located above the delivery end of the magazine and the other below it.

12. In a typographical machine, the combination of a magazine for the type or matrices, and a single escapement to control their release therefrom, the said escapement being provided with two single matrix-engaging portions, one acting inside of the magazine and the other outside of it.

In testimony whereof I hereunto set my hand this eleventh day of November, 1912, in the presence of two attesting witnesses.

DAVID S. KENNEDY.
